NOISE REDUCTION SYSTEM

Eugene O. Selby, Camden, N. J., assignor to Radio Corporation of America, a corporation of Delaware

Application November 19, 1936, Serial No. 111,688

3 Claims. (Cl. 250—20)

The invention relates to the reduction of noise such as that produced in radio receivers and like apparatus by impulses extraneous to the signal, and has for its principal object the provision of 5 an improved apparatus and method of operation whereby the undesired effects of such extraneous or noise producing impulses are minimized or eliminated.

The problem of noise reduction is susceptible of 10 a number of different solutions, some of which involve (1) balancing or neutralizing the effect of the noise impulses, (2) picking up the desired signal at an antenna which is located at a distance from the radio receiver, (3) limiting or clipping 15 the peaks of the noise impulses, (4) utilization of a special transmission circuit or (5) the use of means for automatically short circuiting, open circuiting or otherwise controlling the transmitting efficiency of the signal channel for the duration 20 of the noise producing impulses.

The present invention involves the use of some 25 of these features but is chiefly characterized by the use of a tuned control circuit which (1) rejects the desired signal impulses, (2) accepts and 30 detects the noise impulses and (3) utilizes the resulting detected current to so control a grid bias potential of some stage of the signal channel as to preclude the passage of noise impulses to the final stages of this channel. A further feature 35 of the invention is the provision of a control circuit which is effective to eliminate the effect of noise impulses irrespective of the relative amplitudes of the noise and signal impulses.

The invention will be better understood from 40 the following description when considered in connection with the accompanying drawings and its scope is indicated by the appended claims.

Referring to the drawings:

Fig. 1 is a wiring diagram of a signal channel 45 including a control circuit wherein the noise impulses are detected and utilized to bias an audio frequency stage below cut-off for the duration of the noise signal.

Fig. 2 illustrates a channel which is similar to 50 that of Fig. 1 in several respects but differs therefrom in that the signal and detected noise impulses are applied to different grids of the audio frequency stage,

Fig. 3 illustrates a channel including means for 55 balancing out or neutralizing the detected noise impulses before they reach the audio frequency stage,

Fig. 4 illustrates a signal channel provided with 55 means which operate to eliminate noise down to and including aero level of the signal,

Fig. 5 illustrates a signal channel wherein a bias potential dependent on the detected noise impulses is applied to an intermediate frequency stage instead of to an audio frequency stage, as 5 in the channels of Figs. 1 to 3, and

Fig. 6 illustrates a similar signal channel where- 10 in the noise impulse responsive bias is applied to a detector stage of the channel.

The channel of Fig. 1 includes an intermediate frequency stage 10, a signal detector and noise 10 amplifier and detector stage 11 which may be of the 6B7 RCA Radiotron type, and an audio frequency stage 12 provided with a control grid 13 which is subjected to a resultant bias potential dependent on the detected signal impulses and 15 the amplified and detected noise impulses.

The intermediate frequency stage 10 has its 20 output circuit connected to the detector electrodes 14—15 through a transformer 16 and a resistor 17 which is shunted by a capacitor 18. The stage 10 25 is also provided with diode electrodes 19—20 from which an automatic volume control current is derived for maintaining a substantially constant signal at the control point exemplified in this instance by the electron discharge device 25 11. The maintenance of such a level at this point is advantageous from the viewpoint of segregating the noise impulses which are of relatively high amplitude and frequency.

The electron discharge device 11 is provided 30 with (1) electrodes 14—15 which function to de- 35 tect the signal, (2) a control grid 21 which is subjected to the signal and noise impulses, (3) an amplifier output circuit which is tuned by the transformer primary winding 22, the capac- 35 itor 23 and the inductor 24 to reject the signal 40 impulses and accept the noise impulses, and (4) detector electrodes 15—25 which are connected to the transformer secondary winding 26 through a resistor 27 which is shunted by a capacitor 28. 40 The capacitor 23 and the winding 22 are tuned to a frequency below resonance at the signal 45 frequency to render the reactance of the circuit 22—23 capacitive and of such magnitude as to equal the inductive reactance of the inductor 24 45 in series with it, at the signal frequency. The inductance of the inductor 24 and the capacitive reactance of the circuit 22—23 provides a series resonant circuit in a filter which is responsive to the signal frequency and acts as a rejector cir- 50 circuit at that frequency which lies in the middle of the pass band of the signal transmission channel which may be relatively wide.

With these connections, detected signal im- 55 pulses are applied to the audio frequency stage 55

grid 13 through a coupling capacitor 29 and a direct current bias potential dependent on the noise impulses is applied to the grid 13 through a resistor 39, thus biasing the stage 12 to cut-off 5 for the duration of the noise impulse.

The channel of Fig. 2 is similar to that of Fig. 1 in some respects but differs therefrom in that (1) the intermediate frequency stage 10 is provided with detector electrodes 20-31 and network 32-33-34-35 through which the detected signal impulses are applied to the control grid 13 of the audio frequency amplifier 12, and (2) the electron discharge device 11 is provided with a control grid 21 which is subjected to the signal and noise impulses, with an output circuit 22-23-24-26 tuned to reject the signal impulses and accept the noise impulses and with triode electrodes 15-35-36 which function through a resistor 30 to apply to a grid 37 of the audio frequency stage 12 a bias potential dependent on the noise impulses.

With these connections, the triode grid 35A is subjected to a potential dependent on the noise impulses and the potential developed in the triode output circuit resistors 38-39 is utilized to bias the audio frequency stage 12 to cut off for the duration of the noise impulse. As indicated, the different electron discharge devices may be respectively of 6B7, 6F7 and 6A7 RCA Radiotron types.

The channel of Fig. 3 differs from that of Fig. 2 in that the noise impulses amplified by the stage 11 are detected by a device 40 and applied through a resistor 41 and a capacitor 42 to the terminal of the audio frequency stage control grid 13 in phase opposition to the noise component of the signal impulse applied to this terminal through capacitor 35. The noise impulses are thus neutralized or balanced out to any desired extent by adjustment of the terminal 43 of the resistor 41.

The channel of Fig. 5 includes several features described in connection with the foregoing figures but differs in that the signal is detected and amplified in the audio frequency stage 12 which also provides a source of automatic volume control potential indicated at the terminal 43. Other differentiations from the previous figures are that (1) the signal and noise impulses are applied through parallel circuits to the control grid of the noise amplifier and detector 11 and to the control grid of the intermediate stage 10, (2) the amplified and detected noise impulses are applied to a separate intermediate frequency stage grid 44 for the purpose of biasing this stage to cut off for the duration of the noise impulses, and (3) a noise impulse responsive automatic volume control potential is applied through a terminal 45 to one or more of the preceding radio frequency stages.

The channel of Fig. 6 differs from those previously described in that the amplified and detected noise impulses are utilized to apply to the control grid of a detector 46 a potential which biases this detector to cut off for the duration of the noise impulse and interrupts the channel between the intermediate frequency amplifier 10 and the audio frequency amplifier 12.

Fig. 4 illustrates a connection which may be

utilized to eliminate the effect of noise impulses irrespective of the presence or absence of signal impulses. In this arrangement, the control grid 47 of a noise detector device 48 is returned to the cathode of the intermediate frequency stage 10. With zero signal the grid 47 is positive and the plate current of the device 48 produces in the resistor 49 a potential whereby the audio frequency stage 12 is biased to cut off. When signal impulses are received, the rectified current of resistor 50 biases the grid 47 negative and the device 48 is adjusted to cut off by means of resistor 50. Under these circumstances, negative surges are cut off by the noise detector 48 and positive surges cut off the audio frequency stage 15 for the duration of the noise impulses.

I claim as my invention:

1. The combination of means providing a signal amplifier adapted to receive and amplify signal and noise impulses in a relatively wide band of frequencies, an electron discharge device in said amplifier provided with grid electrode means for controlling the flow of signal and noise impulses, means in said amplifier for subjecting said grid electrode means to a control potential dependent on said signal, means in said amplifier including a single tuned filter circuit for rejecting the desired signal impulses and accepting and detecting the noise impulses, thereby segregating said noise impulses from the signal impulses, and means for subjecting said grid electrode to a bias potential dependent on said segregated impulses.

2. The combination of an intermediate frequency amplifier adapted to receive signal and noise impulses in a relatively wide frequency band, an electron discharge device coupled to said amplifier and provided with a pair of grid electrodes for controlling the signal flow therethrough, means for subjecting one of said grid electrodes to a control potential dependent on said signal impulses, and filter means for receiving signal and noise impulses, said filter means being tuned to a narrow frequency band within said first named band for selectively excluding signal impulses and subjecting one of said grid electrodes to a control potential dependent on said noise impulses.

3. In a radio receiving system, the combination with an intermediate frequency amplifier stage, of means providing a signal detector and a noise amplifier stage, means coupling said signal detector and noise amplifier to said intermediate frequency amplifier stage, a rectifier coupled to said noise amplifier stage, means providing a tuned filter circuit for applying signals from said noise amplifier stage to said rectifier passing a relatively wide band of frequencies on either side of the intermediate frequency and for attenuating signals at the intermediate frequency, and an additional tube in the signal channel of said receiving system having grid electrode means for receiving a controlling potential from the signal detector and from said rectifier operative to preclude the passage of noise impulses therethrough in response to controlling potentials from said rectifier.

EUGENE O. SELBY.
